LIMITED, OF LONDON, ENGLAND

ELECTROMECHANICAL VIBRATION-TRANSLATING DEVICE SUCH FOR EXAMPLE AS
LOUD-SPEAKERS

Application filed July 19, 1928, Serial No. 293,961, and in Great Britain August 5, 1927.

The present invention is concerned with improvements in or relating to electrical devices of the type in which one member is caused to move relatively to another member under the influence of electrically generated forces acting between adjacent surfaces on the respective members or in which electrical oscillations are generated by the relative movement of two members, the movement being at least in part rotational.

If reliance is placed on a mechanical restoring force or on mechanical restoring forces obeying Hook's law for the normal positioning of these members, it is known that inaccurate interconversion of electro-mechanical effects has been obtained hitherto, that is to say, in the case of the conversion of electric currents into mechanical displacements, for example, the relation between current and displacement has not been linear. The extent of the departure from linearity can be reduced by making the working displacements a small fraction of the normal distance apart of the two surfaces, but even if this distance is kept relatively large, the defect is not eliminated, while the sensitivity of the instrument is impaired.

In a companion application No. 257,971 for electrically operated vibratory devices, filed 30 February 29, 1928, which also relates to armatures the vibrational movement of which is at least partially rotational, attention is called to the advantages resulting from the surface of the armature being disposed, when no oscillatory current is passing, at an angle to the surface of the pole pieces which did not change in sign during the vibration of the armature, this disposition being effected either by an inclination of the surface of the 40 reed-support, or by inclining the armature relatively to the reed support, or by a combination of both.

In said application I further described means for adjusting the inclination of the 45 armature surface relatively to that of the pole pieces, for example, by mounting the magnet so that it was rotatable about an axis.

One object of the present invention is to minimize the injurious effect of reactive 50 forces acting upon an armature during vi-

bration due to the load which it drives, or to use these forces to advantage.

Another object of the present invention is to provide an electro-magnetic vibratory device which is efficient and in which a substantially linear relation between applied current and resulting displacement of a point in the armature may be obtained, whether the pole pieces actuating the armature are on the same or on opposite sides of the armature.

A further object of the invention is to provide an efficient electro-magnetic vibratory device in which the magnet poles are both upon the same side of the armature and in which equal and opposite currents fed to the device produce equal and opposite displacements of a point on the armature.

According to one feature of the present invention, in a device of the type set forth, the member to be driven by a vibratory armature, or the member adapted to drive the armature, is connected to the armature at a point (referred to as the point of attachment) situated between the centre and the heel thereof. For the purpose of this specification the armature is to be regarded as those parts of the vibratory member which lie, at any moment, vertically above the stationary co-operating surface (assuming that the stationary surface is disposed horizontally) and the end of the armature nearer the real or virtual axis of rotation thereof will be referred to as the heel of the armature, the opposite end of the armature being referred to as the toe.

According to another feature of the present invention, the armature is so dimensioned and disposed that as it moves from its position of closest proximity to a cooperating surface away from said surface, the point at which the resultant attractive force (referred to as the centre of force) acts, moves towards the toe of said armature.

According to a further feature of the present invention, the parts are so dimensioned and disposed that, as the armature moves, the centre of force moves in such a manner that the moment of the resultant attractive force about the real or virtual axis of rotation of the armature varies according to a substan-

tially linear law with the displacement of the point of attachment (towards and away from the co-operating surface) from the position of rest. In the preferred arrangement the 5 point of attachment is so selected that the centre of force moves from one side to the other side of the point of attachment as the armature moves from its innermost to its outermost working position. It is prefer- 10 ably arranged that the change in the radius of rotation of the centre of force during movement of the armature shall be sufficiently large in relation to the radius itself, to provide compensation for relatively large 15 changes of attractive force.

The invention is illustrated in the accompanying drawings in which Figs. 1 to 3 are views in side elevation plan and end elevation respectively of a part of an electromagnetic vibratory device in accordance with the invention, the view in Fig. 1 being a section on the line R—R of Fig. 2, and 20

Figs. 4 and 5 are diagrams illustrative of the invention.

Referring to Figs. 1-3, a magnet (coils of which are indicated at C) is arranged with its pole pieces 1 and 2 projecting inwards, a small air gap being left between the tips of the pole pieces and the magnetic circuit being 25 closed excepting for this air gap. The upper surfaces of the pole pieces adjacent the air gap, which will be referred to as the pole surfaces, will be regarded as one of the surfaces above referred to, namely the fixed surface. 30 An armature 3, the under surface of which acts as the other surface above referred to, namely the movable surface, is carried upon a cross piece 4 which is clamped at its two ends by means of screws passing through holes 5. The armature may therefore be 35 regarded as mounted for rotational vibration about an axis 6 which is upon the centre line of the cross piece 4. The cross piece 4 is thus adapted to twist and furnish the required re- 40 storing force. The width of the armature is, as shown, greater than the width of the air gap. The under surface of the armature will at first be considered to remain flat and for 45 simplicity, its plane will be assumed to contain the axis of rotation 6, since very little error is introduced by this latter assumption. The axis of rotation of the armature surface will thus be assumed to be at B (Fig. 1). The 50 law of magnetic force between the two surfaces is a complex one, but it may be assumed with sufficient accuracy for many practical purposes that the total magnetic force is 55 equal to

$$60 \quad c \int_0^p \frac{dx}{(y+A)^2} \quad (1)$$

where c is a constant, dx is an element of 65 length along the armature, (that is in a direc-

tion normal to the axis B), y is the distance between the element dx and the pole surface measured along its arc of rotation, p is the width of the magnet poles, the distance x being measured from the edge of the poles 70 nearer the axis of rotation, and A is a constant. It is interesting to note that the constant A may be regarded as the length of air gap (having the same cross section as the working air gap between armature and poles) 75 which has the same reluctance as the iron path. A will be referred to as the equivalent minimum air gap.

In order to ascertain the distribution of magnetic force for any position of the armature within working limits, it is convenient to determine the point in the armature about which the sum of the moments of the magnetic force is zero. This is found to be represented by the equation:

$$a = mp \left(\frac{n+k}{n+1} \right) \left\{ \left[\frac{(n+k)m}{n+1} \right] \log_e \left[1 + \frac{n+1}{m(n+k)} \right] - 1 \right\} \quad (2)$$

where

$$k = \frac{A}{\delta}, m = \frac{r}{p}, n = \frac{b}{\delta}, \delta \text{ the distance,}$$

in a vertical plane through the axis of rotation of the armature, between the co-operating surfaces upon the armature and the magnet poles δ being measured as positive when the two planes intersect between the axis of rotation of the armature and the co-operating 95 surfaces, b is the value of y (that is to say the length of air gap) at the heel of the armature, a is the distance of the centre of force from the heel of the armature and r is the distance of the axis of rotation from the 100 nearer edge of the poles. The resultant magnetic force may be regarded as acting at this point distant a from the heel of the armature.

From Equation (2) the interesting fact 110 may be shown that if $k=1$ the centre of force does not move during displacement of the armature. In other words, if the axis of rotation of the armature (considered of course to lie in the plane of the armature surface) 115 is situated below the plane of the magnet poles by an amount equal to the equivalent minimum air gap, the centre of force remains a fixed point in the armature during movement of the armature.

For under these conditions we have:

$$120 \quad a = \frac{r}{p} (r+p) \log_e \left(\frac{r+p}{p} \right) - r \quad (3)$$

and thus a is seen to be independent of b .

If the axis of rotation is above this (that is if $\delta < A$) the centre of force will move towards the heel of the armature as the armature moves away from the magnet poles.

If $\delta > A$ the centre of force moves towards

the toe of the armature as the armature moves away from the magnet poles.

In Fig. 4 there is illustrated diagrammatically an imaginary case in which $\delta > A$ and in which the armature 3 is constrained to execute parallel motion, that is to say, r is made infinite, the armature being shown in two positions, the full line position being that of contact at one end with the pole 2 and the dotted line position being further from the pole. The position of the centre of force in the two armature positions is indicated by the arrows.

It has been found that, when a vibratory device of the type shown in Figs. 1 to 3 is used to drive the conical diaphragm of a loud speaker through the rod 7, there is one position of the point of attachment of the diaphragm to the armature which gives better results than any other, particularly in regard to the reproduction of the lower tones, and this position has always been found to lie between the centre and the heel of the armature. The best point is usually found to be at a distance from the heel of the armature between $\frac{1}{3}$ and $\frac{2}{3}$ of the length of the armature, or in other words between one-sixth and one-tenth of the length of the armature back from the centre thereof, measured in a direction normal to the axis of rotation thereof. It has also been found that this optimum position approximately coincides with the position of the centre of force in the position of rest of the armature, and when the armature moves from its innermost to its outermost position during vibration, the centre of force moves from one side of the point of attachment to the other side thereof.

A possible explanation of this will be given later.

The movement of the centre of magnetic force towards the axis of rotation of the armature as the armature approaches the poles indicated by Equation (2) is utilized, according to a feature of the present invention, to assist in providing a linear relation between the current passed through coils surrounding the magnet poles and the displacement of the point of attachment produced by the current while maintaining efficiency by allowing the armature in its innermost position at maximum amplitude to all but make contact with the poles.

It is known that the magnetic force on an armature increases too rapidly at small air gaps as compared with the change at larger air gaps to give such a linear relation if a restoring force obeying Hook's law is used and if the distribution of the magnetic force in the armature remains constant. Moreover, for simplicity and cheapness it is highly desirable to use a restoring force of this nature. According to the present invention the centre of magnetic force is, by suitable dimensioning and disposition of the parts,

caused to move towards the axis of rotation of the armature, as the armature approaches the poles, in such a manner that the product of the magnitude of the force and the distance from the axis of rotation at which it acts (in other words the moment of the resultant magnetic force) changes at a rate which is substantially constant for all equal displacements of the armature within its working range.

It will be clear that any given movement of the centre of force will have a greater effect if the radius of rotation of the armature is short in relation to the length of the armature than if it is large and it has been found that for most purposes it is desirable that the length of the armature should be at least equal to the distance between the heel of the armature and the axis of rotation.

It is emphasized here that Equation (2) is only true if the armature is of such stiffness that its flexure can be disregarded. With such an armature it is found that in most practical cases the value of δ has to be made rather high in order to get a sufficient movement of the centre of force to give a sufficiently close approach to linearity, and this leads to lack of sensitivity. It has however, been discovered that if the armature be made so that its flexure due to the forces acting upon it is not negligible, this flexure can be made to assist in securing linearity. No rule for determining the optimum flexibility can be given but, with the assistance of the probable explanations of the manner in which the flexibility affects the performance given below, the best value in any particular case can readily be found experimentally. Dimensions of one working arrangement are also given.

It can be shown that when the air gap is small in relation to A so that the square of the air gap length can be neglected, the force of attraction is proportional to

$$\frac{A-2y}{A^3},$$

where y is the air gap length. Thus at such small air gaps the attractive force varies in a linear manner although at too great a rate and a relatively slow movement of the centre of force is required, the rate of movement preferably tending towards zero at contact, whereas at larger air gaps it is of advantage to increase the movement of the centre of force over what is normally given by a plain rotational movement. Flexing of the armature tends to fulfil both these desiderata.

In estimating the effect of the magnetic force in producing flexure we may regard the armature as a beam anchored at the heel of the armature. This will of course only be the case if, as in the device shown in Figs. 1-3, the armature is considerably more flexible than the member between it and the cross bar.

Thus the arm of the moment of the resultant magnetic force is shorter in this case than when rotation about the axis of rotation of the armature is being considered and a small movement of the centre of force will consequently have a greater effect. In both the innermost and outermost armature positions, flexure tends to reduce the toe air gap, that is to say, the effect in both cases is to make the armature move more nearly parallel to itself than it would if it did not bend. If one surface moves parallel to itself and parallel to a co-operating surface, the centre of force does not move. If one surface moves parallel to itself but at an angle to a co-operating surface, the movement of the centre of force is greater than it would be with pure rotational movement. Thus it would appear that the flexure tends to reduce the movement of the centre of force towards the heel when the armature approaches the magnet pole and to increase the movement of the centre of force towards the toe when the armature moves outwards. If the arrangement is such that the amount of flexure is greater, owing to the movement of the centre of force (which may be regarded as acting at a short arm) in the outermost armature position than in the innermost position, the effect of flexure will be, as stated, to assist in giving the linear relation desired.

Fig. 5 is a diagram illustrating the foregoing and also offering a possible explanation of the advantage of connecting a diaphragm to the armature at a point between the centre and the heel of the armature. The armature 3 is shown in full lines in its outermost position during vibration and in dotted lines in its innermost position. The armature is flexible and the disposition and direction of the forces acting upon it in the two positions are indicated by the arrows. M_1 and M_2 are the resultant magnetic forces in the two positions respectively, L_1 and L_2 are the forces at the point of attachment due to the mass of the diaphragm or other driven load and R_1 and R_2 are the mechanical restoring forces. It will be seen that there is a tendency for the system of forces apart from the dynamic forces to produce flexure of the armature in such a manner that the point at which the force M_1 acts is nearer the toe of the armature than if the flexing did not take place. The force M_2 will also act at a point which is further from the heel than if the armature remained straight but, as already stated the flexure may be made greater in the outermost position than in the innermost position, and consequently the general effect is to increase the total movement of the centre of force and to reduce its rate of movement as the armature approaches the poles, and therefore to permit of a smaller inclination between the co-operating surfaces in their closest position (thus giving sensitivity) for any given con-

ditions as to the desired closeness of approach to linearity.

If the centre of force moves as shown from one side to the other side of the point of attachment during movement of the armature, it can be shown (for any given position of say the heel of the armature and taking into account the fact that for equilibrium the moments of the forces, L_1 and M_2 about B , in the dynamic case, must equal the moment of the force M_1 alone about B , in the static case) that the inertia forces L_1 and L_2 both tend to increase the flexing effects which take place statically and which have been described above.

For the ratio of the flexing moment when the inertia force is acting to that when the inertia force is not acting is equal to

$$1 + \frac{L_1(p-q)}{R_1(p-1)} \quad (4) \quad 85$$

for the full line position of Fig. 5, where p and q are the ratios of the distances of the forces M_1 and L_1 respectively from the axis B to the distance of the force R , from that axis.

The equivalent to expression (4) for the dotted line position of Fig. 5 is

$$1 + \frac{L_2(q-p)}{R_2(p-1)} \quad (5) \quad 95$$

where p and q have the same significance in relation to forces L_2 and M_2 as they had in expression (4) in relation to L_1 and M_1 .

It will be seen from these two expressions that if $p > q > 1$ in expression (4) and if $q > p > 1$ in an expression (5), the flexure is increased by the inertia force in both positions of the armature.

Moreover it appears desirable from these expressions that L_1 and L_2 should attain zero value when p becomes equal to q in order that the arrangement should be symmetrical and to prevent the introduction of harmonics, and this is apparently equivalent to stating that the load should be attached to the armature at a point which is coincident with the centre of force in the position of rest of the armature.

It should be pointed out that the amount of flexure which has been found desirable in practice is extremely small, for example of the order of 0.01 m/m, but since the total amplitude of vibration of the point of attachment may not exceed 0.05 m/m and the final air gap will be a small fraction of the amplitude, it will be clear that a small amount of flexure may have a very important effect.

In order to decrease the size of the minimum air gap where a flexible armature is used, it may sometimes be desirable to shape one or both of the co-operating surfaces in such a manner that a closer approach to uniform contact over the whole of the surfaces is obtained after the armature has flexed than

is possible if both surfaces are flat when the armature is unstressed.

In ascertaining statically the correct relative positions of the armature and magnet poles it is convenient to adjust the height of the platforms upon which the cross bar is clamped, for example by the insertion or removal of packing washers placed between the cross bar and the platform in the neighbourhood of the holes 5. After each adjustment the relation between applied current and displacement of the point of attachment is determined, for example with the aid of a Kelvin optical lever, and this is continued until the desired relation is obtained.

The final test will, however, in a vibratory device be a dynamic one and for this purpose a number of different pure frequency electrical oscillations may be fed successively to the device and either a record may be made of the wave form of the mechanical oscillations produced (for example by optical means) or the percentage of harmonic frequencies produced may be measured with the aid of suitable filters.

In one loud speaker movement embodying the present invention, the magnet pole surfaces are mounted for rotary adjustment about an axis in their plane and in the same vertical plane as the point B.

If the device is intended to work over a considerable range of maximum amplitudes it has been found advantageous however, to make the radius of rotation of the magnet pole surfaces less than above stated in order to secure greater uniformity of performance at different settings of the adjusting means. In one case the radius of rotation of the magnet poles was reduced by 2 m/m with good results. The cross bar is mounted upon a platform the upper surface of which is 0.02 m/m below the axis of rotation of the magnet poles. The length of the cross bar between the end supports is 38 m/m, the depth of the cross bar is 5 m/m and its width 1.2 m/m. The radius of rotation of the heel of the armature is 6.0 m/m, the length of the armature is 9.6 m/m, the thickness of the armature 1.7 m/m and its width 6 m/m. The magnet is a U-shaped cobalt steel magnet (36% cobalt) 145 m/m in length along the centre line, including the pole pieces, and having a cross sectional area of 85 sq. m/m. The air gap between the pole pieces is 2.3 m/m. The point of attachment is 1.2 m/m back from the centre of the armature.

Although the invention has been described as applied to an armature with one particular type of restoring force, it is not so limited. A pivoted armature with a separate restoring force may be used or a cantilever reed may be employed and the armature portion of the reed may then be considered to rotate

about a virtual axis as described in my prior application No. 257,971.

I claim:—

1. A vibratory device comprising an armature mounted for vibration about an axis, a magnet pole surface adapted to co-operate with a surface of said armature, means adapted to vary the force between the armature and magnet pole surface in accordance with electrical oscillations, a member adapted to be driven by said armature, and means connecting the armature with said member, said connecting means being attached to the armature at a point situated between the centre of said cooperating surfaces and the ends thereof nearer said axis. 70 75 80

2. A device for the inter-conversion of electrical and mechanical energy comprising an armature mounted for vibration about an axis, a magnet pole surface adapted to co-operate with a surface of the armature, and means, adapted to transmit mechanical vibratory energy, connected to the armature at a point situated between the centre of said cooperating surfaces and the ends thereof nearer said axis. 85 90 95

3. A device as claimed in claim 2, wherein said point of attachment is at a distance from the centre of the cooperating surfaces equal to between $\frac{1}{6}$ and $\frac{1}{10}$ of the radial length of said surfaces and between said centre and the axis. 100 105 110

4. A device for the inter-conversion of electrical and mechanical energy comprising an armature mounted for vibration about an axis, a surface adapted to cooperate with said armature, means for providing an attractive force between the armature and said surface, restoring means for the armature, and means, adapted to transmit mechanical vibratory energy, attached to the armature at a point within the magnetically active part of the armature, whereby the centre of attractive force will move from one side to the other side of said point as the armature moves, during vibration, from its position of closest proximity to said surface to its position furthest from said surface. 115 120 125 130

5. A device for the inter-conversion of electrical and mechanical energy comprising an armature mounted for vibration about an axis, a surface adapted to cooperate with the armature, and means for providing an attractive force between the armature and said surface, the side of said armature adjacent said surface being of convex form when the armature is unstressed.

6. A device for the inter-conversion of electrical and mechanical energy comprising an armature mounted for vibration about an axis, a convex surface adapted to cooperate with said armature, and means for providing an attractive force between said armature and said surface. 125

7. A vibratory device comprising an arma- 130

- ture mounted for vibration about an axis, a magnet pole surface adapted to co-operate with a surface of the armature, means adapted to vary the force between said cooperating surfaces in accordance with electrical oscillations, a member adapted to be driven by the armature, and means connecting the armature with said member, said means being connected to the armature at a point situated between the centre of said cooperating surfaces and the ends of said surfaces near said axis, and the radial length of said cooperating surfaces being at least $\frac{2}{3}$ of the radius of rotary vibration of the centre of said cooperating surfaces.
8. A device for the inter-conversion of electrical and mechanical energy comprising an armature mounted for vibration about an axis, a magnet pole surface adapted to co-operate with a surface of the armature, and means, adapted to transmit mechanical vibratory energy, connected to the armature at a point within the magnetically active part thereof.
- 25 9. A device for the inter-conversion of electrical and mechanical energy comprising an armature mounted for vibration about an axis, a magnet pole surface adapted to co-operate with a surface of the armature, means for providing an attractive force between the armature and said surface, and restoring means for said armature, the radial length of the said cooperating surfaces being at least $\frac{2}{3}$ of the radius of rotary vibration 35 of the lengthwise centre of said surfaces and the disposition of the armature being such that the centre of attractive force thereon will move away from said axis when the armature moves during vibration from its position of closest proximity to said surface to its position furthest from said surface.
- 40 10. A device for the inter-conversion of electrical and mechanical energy comprising an armature mounted for vibration about an axis, a magnet pole surface adapted to co-operate with a surface of the armature, means for providing an attractive force between the cooperating surfaces, and restoring means for said armature, the radial length of said 45 cooperating surfaces being at least $\frac{2}{3}$ of the radius of rotary vibration of the lengthwise centre of said cooperating surfaces and the disposition of the armature being such that the point in the armature at which the resultant attractive force upon the armature acts, moves so that the moment of said resultant force above said axis varies according to a substantially linear law with the displacement of a point on the armature towards and away from said surface.
- 55 11. A vibratory device comprising an armature mounted for vibration about an axis, a magnet pole surface adapted to co-operate with a surface of the armature, means 60 adapted to vary the force between said co-

operating surfaces in accordance with electrical oscillations, a member adapted to be driven by the armature, and means connecting said member to the armature at a point situated in the magnetically active part of the armature between the centre of said co-operating surfaces and the end of said surfaces nearer said axis, the portion of the armature which co-operates with said pole surface being flexible in relation to the portion thereof between said co-operating surfaces and axis.

70 12. A device for the inter-conversion of electrical and mechanical energy comprising an armature mounted for vibration about an axis, a magnet pole surface adapted to co-operate with a surface of the armature, and means, adapted to transmit mechanical vibratory energy, connected to the armature at a point situated between the centre of said co-operating surfaces and the ends of said surfaces nearer said axis, the portion of the armature which co-operates with said pole surface being flexible in relation to the portion thereof between said co-operating surfaces and axis.

75 13. A device for the inter-conversion of electrical and mechanical energy comprising an armature mounted for vibration about an axis, a magnet pole surface adapted to co-operate with a surface of the armature, means for providing an attractive force between said co-operating surfaces, restoring means for the armature, and means, adapted to transmit mechanical vibratory energy, attached to the armature at a point within the magnetically active portion of the armature, whereby the centre of attractive force is adapted to move from one side to the other side of said point when the armature moves, during vibration, from its position of closest proximity to said surface to its position furthest from said surface, the portion of said armature which co-operates with said pole surface being flexible in relation to the portion thereof between said co-operating surfaces and axis.

80 100 110 120 125 130 In testimony whereof I have signed my name to this specification.
